UNITED STATES PATENT OFFICE.

THOMAS FAULDER, OF SYRACUSE, NEW YORK, ASSIGNOR TO HARVEY A. MOYER, OF SYRACUSE, NEW YORK.

DUMP-WAGON.

SPECIFICATION forming part of Letters Patent No. 769,944, dated September 13, 1904.

Application filed May 17, 1904. Serial No. 208,331. (No model.)

To all whom it may concern:

Be it known that I, THOMAS FAULDER, of Syracuse, in the county of Onondaga, in the State of New York, have invented new and 5 useful Improvements in Dump-Wagons, of which the following, taken in connection with the accompanying drawings, is a full, clear, and exact description.

This invention relates to improvements in 10 dump-wagons in which the dump-box is provided with laterally-swinging bottom doors meeting at substantially the longitudinal center of the box, and refers more particularly to the mechanism by which these doors are 15 raised and lowered. In this class of dump-wagons a rotary drum or shaft is usually mounted in a horizontal position transversely of the box at or near its front end and is connected by suitable chains or cables to the 20 meeting edges of the doors, so that by rotating the drum in one direction the doors are closed and are free to swing to their open position by gravity when the drum is released, thus rotating the drum in the opposite direction. 25 My object is to simplify the means by which this drum is rotated and released by providing a single operating-lever with two pawls at opposite sides of its fulcrum, both of which act upon the ratchet-wheel on the 30 drum as the lever is operated in reverse directions to rotate said drum, and thereby effect a rapid closing of the doors. Another object is to provide means whereby one of these pawls may be operated by hand to not 35 only release itself, but also to engage and release the other pawl for releasing the drum and permitting the doors to swing to their open positions in the act of dumping the load.

Other objects and uses will be more clearly 40 brought out in the following description.

In the drawings, Figure 1 is a side elevation of a front portion of a dump-box and my improved drum-operating mechanism mounted thereon. Fig. 2 is a section on line 2 2, 45 Fig. 1, of the parts seen in Fig. 1, the doors in both views being shown in their closed positions and the operating-pawls as engaged with the ratchet-wheel. Fig. 3 is an enlarged detail view of the ratchet-wheel and pawls

and operating-lever, the lever being shown as 50 rocked forwardly to the limit of its forward movement, and therefore the pawls are separated to the limit of their separation. Figs. 4 and 5 are views similar to Fig. 3, showing the operation of the pawls and lever in releasing the drum, one pawl being released in Fig. 4 and both pawls released in Fig. 5.

Similar reference characters indicate corresponding parts in all the views.

In order to demonstrate the utility of my 60 invention, I have shown a portion of a dump-wagon box 1, having swinging bottom doors 2, hinged to the lower edges of the sides of the box and meeting at substantially the longitudinal center of said box. A suitable 65 drum 3 is journaled on the front end of the box in front of the front end wall 4 and is connected by chains or cables 5 and 6 to the meeting ends of the doors, the manner of connection being similar to that set forth in Patent No. 754,228, dated March 8, 1904; but as the matter of connection of the chains with the doors and drum is immaterial it is unnecessary to further illustrate or describe the same, except to state that the winding of the drum 70 in one direction operates to close the doors, and the release of the drum permits the doors to swing to their open position by gravity. In this instance I have shown one end of the drum as protruding from one side of the 80 box and provided with a ratchet-wheel 7. A bracket 8 is secured to the adjacent side of the box, and to this bracket is fulcrumed at 9 a hand-lever 10, carrying two pawls 11 and 12, which are pivoted, respectively, at 13 and 85 14 to the lever equidistant from and at opposite sides of the fulcrum 9. Both of these pawls are engaged with the teeth of the ratchet-wheel in the operation of winding the cables 5 and 6 upon the drum 3 to close the 90 doors 2; but the pawl 11 is somewhat longer than and overreaches the pawl 12 and is provided on its lower face with a series of notches or shoulders 15, while the pawl 12 is provided with a nib or shoulder 16. These shoulders 95 15 and 16 are located at the front side of the fulcrum 9, and when the lever is drawn to its upright position, as seen in Figs. 1 and 5, the

notches or shoulders 15 lie in the path or the upward-swinging arc of the shoulder 16.

To the upper end of the lever 10 is pivoted a rocking handpiece 20, which is connected by a link 21 to a lug or pin 22 on the inner face of the pawl 12 between the shoulders 16 and pivot 14, so that the operator may grasp the upper end of the lever 10 and free end of the rocking arm 20 simultaneously, and thereby 10 elevate the pawl 12 out of engagement with the ratchet-wheel 7, as seen in Figs. 4 and 5; but this pawl 12 is preferably held in engagement with the teeth of the ratchet-wheel by its own gravity, aided by a spring 23, which 15 is located between the rocking member 20 and the adjacent side of the lever 10.

In rotating the drum to wind the cables 5 and 6 thereon in the operation of closing the doors the forward movement of the lever 10 20 brings the pawl 11 into operative engagement with the teeth of the ratchet-wheel to rotate the same in one direction, while the rearward movement of the lever 10 brings the pawl 12 into action to continue the movement of the 25 ratchet-wheel in the same direction, and it is therefore seen that the winding movement of the drum is substantially continuous, because the pawls 11 and 12 operate to rotate it in the same direction, while the lever 10 is being 30 moved in the reverse directions back and forth, thereby affording a rapid closing operation of the doors. Now when it is desired to release the drum to permit the doors to swing to their open or dumping positions it is simply 35 necessary to swing the lever 10 to nearly an upright position, or a little farther back than the position seen in Fig. 4, until one of the shoulders 15 is brought into the path of upward movement of the shoulder 16 of the 40 pawl 12, whereupon the lever 10 is pushed slightly forward sufficient to relieve the strain on the pawl 12, which is then raised by compressing the rocking member 20 until the rib 16 engages one of the notches 15. The pawl 45 12 is held in this elevated position and the lever 10 is then drawn rearwardly a slight distance, thus causing the nib 16 to engage or bite on the adjacent face of the pawl 11, which throws said pawl 11 out of engagement with 50 the ratchet-teeth, thus liberating the drum and doors connected thereto. It is evident from this latter description that owing to the proximity of the pivot 14 of the pawl 12 to the fulcrum 19 a considerable leverage is obtained 55 to lift the pawl 11 out of holding engagement with the ratchet-wheel.

By locating the pawls 11 and 12 on opposite sides of the fulcrum of the lever 10 it is evident that both pawls act as detents to hold 60 the ratchet-wheel and its drum against retrograde movement and that the strain is therefore thrown upon the fulcrum 9, so that the lever 10 may be stopped at any angle or position and still maintain both pawls in their holding positions.

The foregoing description of the construction and operation of my invention is believed to be sufficiently clear and full to enable any one skilled in the art to make, use, and construct my invention.

The bracket 8 is formed with limiting stops or shoulders 25 and 26, which serve the double purpose of limiting the forward and rearward movement and also as a safeguard against accidental release of the drum in case 75 one of the pawls should be accidentally displaced from its holding position. For example, should the pawl 12 be accidentally disengaged from the teeth of the ratchet-wheel the action of said wheel on the pawl 11 would only 80 throw the lever 10 against the stop 26, while if the pawl 11 should be displaced from its holding position the lever would be thrown against the limiting-stop 25.

Having thus described my invention, what 85 I claim, and desire to secure by Letters Patent, is—

1. In a dump-wagon, the combination with a dump-box having swinging bottom doors, a rotating drum, cables connecting the drum 90 to the doors, a ratchet-wheel on the drum, a pivoted lever, pawls mounted on the lever at opposite sides of the fulcrum and engaging said ratchet-wheel to rotate the drum in the same direction as the lever is rocked in reverse directions, and means to draw one of the pawls out of engagement with the ratchet-wheel and into engagement with the other pawl to release the latter pawl from holding 95 engagement with the ratchet for the purpose 100 of releasing the drum.

2. In a dump-wagon, the combination of a dump-box having swinging bottom doors, a rotary drum connected to close the doors, a ratchet-wheel on the drum, a hand-lever fulcrumed at one side of the axis of the drum, pawls pivoted to the lever on opposite sides of its fulcrum and extending in the same direction from said fulcrum and engaging the teeth of the ratchet-wheel whereby said 110 ratchet-wheel and drum are rotated in the same direction by the reverse movements of the lever, one of the pawls having its free end lying over the free end of the other pawl, and means to elevate the free end of the lower 115 pawl into engagement with the upper pawl, whereby said pawls are thrown out of holding engagement with the ratchet-wheel.

3. In a dump-wagon, the combination of a dump-box having swinging bottom doors, a rotary drum connected to said doors to close the same, a ratchet-wheel on the drum, a bracket on the box, a lever fulcrumed on the bracket above the ratchet-wheel, a pawl pivoted to the lever below its fulcrum and engaging the teeth of the ratchet-wheel, a second pawl pivoted to the lever above its fulcrum and also engaging the teeth of the ratchet whereby said ratchet-wheel and drum are rotated in the same direction as the lever is 125 130

rocked back and forth, shoulders on the adjacent faces of the pawls, and means for elevating the lower pawl to bring it into engagement with the shoulders of the upper pawl 5 whereby both pawls are thrown out of operative engagement with the ratchet-wheel to release the drum and doors.

4. The combination with the swinging doors, winding-drum and connections between 10 the winding-drum and doors, of a ratchet-wheel connected to rotate the drum, the lever and limiting-stops therefor, and pawls on the

lever at opposite sides of its fulcrum and engaging said ratchet-wheel, both pawls operating to rotate the ratchet-wheel in the same 15 direction as the lever is rocked back and forth and also holding the ratchet-wheel from retrograde movement.

In witness whereof I have hereunto set my hand this 9th day of May, 1904.

THOMAS FAULDER.
